UNITED STATES PATENT OFFICE.

ORSON HENRY HODGES, OF PORTLAND, OREGON.

ROTARY VALVE FOR INTERNAL-COMBUSTION ENGINES.

Application filed December 23, 1926. Serial No. 156,608.

This invention relates to internal combustion engines and is directed more particularly to a fluid cooled rotary valve for such engines.

5 The primary object of the present invention is to provide a particularly simple form of rotary valve which shall consist of few parts that are simple in construction and inexpensive to manufacture.

10 Another object is to provide a valve of this character which shall include means for effectively lubricating the same, and also means for cooling the valve, the latter being accomplished by connecting such valve in 15 the fluid cooling system of the engine.

With these and other objects in view, the invention may be stated to consist in the various novel features of construction and arrangement or combination, all of which 20 will be fully described hereinafter and pointed out in the appended claims.

In the drawings accompanying and forming part of the application:—

Figure 1 is a vertical sectional view 25 through the upper portion of an internal combustion engine cylinder showing the same equipped with a valve constructed in accordance with my invention;

Figure 2 is a similar view but showing 30 the valve rotated through 90° from the position shown in Figure 1;

Figure 3 is a horizontal sectional view taken on the line 3—3 of Figure 2;

Figure 4 is an elevation of the valve;

35 Figures 5 and 6 are horizontal sectional views taken on the lines 5—5 and 6—6 respectively of Figure 4; and

Figure 7 is a bottom plan view of a cylinder head plate employed for a four cylinder motor and showing a portion of the 40 oiling system for the valves.

45 Describing the various parts by reference characters, 1 denotes the cylinder water jacket of an internal combustion engine and 2 the water jacket of the head 3 of such engine. These water jackets are interconnected in the usual manner by a plurality of aligning apertures 4 so that the cooling fluid may circulate from one to the other.

50 Journalled in the cylinder head 3 in axial alignment with each piston is a rotary valve 5. This valve consists of a cylindrical body portion 6 and an upwardly extending hollow stem 7. As shown particularly in Figure 1, the body portion 6 is hollow to receive cooling fluid therein and the stem 7

is formed with a vertical partition 8, which extends into the body portion and defines an intake and a discharge passage therefor. It will also be noted that the body portion 6 of the valve is formed with a port 9, which, when the valve is rotated, as will be explained hereinafter, is adapted to align with suitable intake, ignition and exhaust ports 10, 11 and 12 respectively, and establish communication between these ports and the engine cylinder.

55 The valve 5 is journalled on bearings 14 and 15, which are disposed about the stem 7. The former of these bearings is disposed

in a recess formed on the body portion 6 and is interposed between such portion and a plate 16 carried by the cylinder head, while the latter of these bearings is inter-

posed between said plate and a helical gear 75 17 that is keyed to stem 7. Bearing 14 re-

ceives the thrust due to the explosion in the engine cylinder and bearing 15 receives the driving thrust of the helical gear 17, such gear being driven by a second helical gear 80

18 carried by a horizontal shaft 19 that may be driven by the engine in any suitable manner. In order to effect a seal between the

valve 5 and the head 3, I provide the body portion of the valve with a plurality of 85 rings 20 which are seated in circumferential grooves 21 formed therein. These rings are

adapted to snugly engage the walls of the cylinder head and loosely engage the grooves in the valve so that as the valve rotates, the 90

rings will remain stationary and rotation will occur between the rings and ring grooves.

Positioned on top of plate 16 is a water cooled casing 23 which communicates with 95 the intake of the valve stem 7 and also with the water jacket of the cylinder head by means of apertures 24. A gland nut 25

threaded on the upper end of the valve stem prevents water from seeping into the driving gears and bearings. As shown particularly in Figure 1, I preferably employ studs 26 to fasten casing 23, plate 16, and head 3 to the cylinder block so that removal of these studs will permit ready access to all parts.

100 As shown in Figures 1, 2 and 7, plate 16 is formed with a longitudinal bore 28 through which oil may be forced from the crank case of the motor by the usual oil pump, or by a separate pump 29 which may 110 be connected with any suitable source of oil not shown. Oil entering bore 28 is dis-

tributed through ports 30 to the lower bearings 14 and thence floods upwardly around the stem 7 to the upper bearing 15 and driving gears. The oil escapes from each valve bearing through a transverse bore 31 in plate 16 and thence through a manifold 32 back to the source of oil supply.

In operation, the valve is timed so that the valve port 9 aligns with the ports 10, 11 and 12 in the usual relation to the stroke of the piston 34 to admit the charge, compress the same, fire it and then exhaust the burnt gases. The heat developed by the explosions is dissipated by the cooling fluid which is pumped from the bottom of the radiator, (not shown) to pipe 36, thence downwardly through nipples 35 to the intake passage of each valve stem 7 and into the body portion of the valve, then beneath partition 8 and upwardly through the discharge passage of the valve stem to casing 23. From casing 23, the cooling fluid flows through apertures 24 to the water jacket 2 of the engine head, then through apertures 4 to the cylinder water jacket and finally back to the radiator in the usual manner not shown.

It is thus apparent that the valves are effectively cooled and lubricated during operation and when desired, access to the various parts may be easily obtained by removing studs 26.

What I claim is:—

1. An internal combustion engine comprising a cylinder, a head carried by said cylinder, a rotary valve journalled in said head and having a hollow valve stem projecting therethrough, a partition dividing said stem into an inlet and a discharge passage and extending into the hollow portion of said valve, a fluid cooled casing carried by said head and communicating with the cooling jacket of said head and with said valve stem, and means for continuously circulating the cooling fluid in said head through said casing, valve stem and valve.

2. An internal combustion engine comprising a cylinder, a head carried by said cylinder, a rotary valve journalled in said head, said valve comprising a hollow body portion and a hollow stem projecting through said head, said stem being provided with a partition defining an inlet and a discharge passage, and means for circulating a cooling fluid through said inlet passage in the stem to the valve and out said discharge passage.

3. An internal combustion engine comprising a fluid cooled cylinder, a fluid cooled head carried by said cylinder, a rotary valve journalled in said head and having a hollow valve stem projecting therethrough, said valve being hollow and said valve stem being formed with a partition dividing said stem

into an inlet and discharge passage extending into the hollow portion of said valve, a fluid cooled casing carried by said head, and means for continuously circulating the cooling fluid of said cylinder through said head, casing, valve stem and valve.

4. An internal combustion engine comprising a cylinder, a cooling fluid jacketed head carried by said cylinder, a rotary valve journalled in said head and having a valve stem projecting therethrough, said valve and valve stem being hollow, a partition dividing said stem into an inlet and a discharge passage and extending into the hollow portion of said valve, a fluid cooled casing carried by said head and connected with the cooling fluid jacket thereof, and a second connection between said casing and the inlet of said valve stem.

5. An internal combustion engine comprising a cylinder, a head carried by said cylinder, a rotary valve journalled in said head and having a valve stem projecting therethrough, a plate carried by said head, a thrust bearing interposed between said plate and said valve and adapted to receive the thrust from the explosive force in the engine cylinder, a driving gear carried by said valve stem, means for rotating said gear to operate said valve, and means for circulating a cooling fluid through said valve stem and valve.

6. An internal combustion engine comprising a cylinder, a head carried by said cylinder, a rotary valve journalled in said head and having a valve stem projecting therethrough, a plate carried by said head, a thrust bearing interposed between said plate and said valve and adapted to receive the thrust from the explosive force in the engine cylinder, said plate being formed with a bore connecting with said bearing and a source of oil, and means for supplying oil to said bore and bearing.

7. An internal combustion engine comprising a cylinder, a head carried by said cylinder, a rotary valve journalled in said head and having a valve stem projecting therethrough, a plate carried by said head, a thrust bearing interposed between said plate and said valve and adapted to receive the thrust from the explosive force in the engine cylinder, a driving gear carried by said valve stem, a second thrust bearing interposed between said plate and said gear and adapted to receive the driving thrust from said gear, said plate being formed with a bore communicating with one of said bearings, and means for circulating a supply of oil to each of said bearings.

In testimony whereof I affix my signature.

ORSON HENRY HODGES.
